UNITED STATES PATENT OFFICE.

JEROME P. CURRAN, OF TOLEDO, OHIO, ASSIGNOR TO THE AMERICAN BOTTLE COMPANY, OF TOLEDO, OHIO, A CORPORATION OF OHIO.

DESIGN FOR A BOTTLE.

Application filed January 12, 1927. Serial No. 20,351. Term of patent 14 years.

To all whom it may concern:

Be it known that I, JEROME P. CURRAN, a citizen of the United States, residing at Toledo, in the county of Lucas and State of Ohio, have invented a new, original, and ornamental Design for Bottles, of which the following is a specification.

Figure 1 is an elevation view of a bottle, showing my new design. Fig. 2 is a fragmentary side elevation looking at one corner

of the bottle. Fig. 3 is a fragmentary side elevation. Fig. 4 is a sectional view taken substantially at the line IV—IV of Fig. 2.

I claim:

The ornamental design for a bottle, substantially as shown.

Signed at Toledo, in the county of Lucas and State of Ohio, this 8th day of January, 1927.

JEROME P. CURRAN.
